US0D1044794S

(12) **United States Design Patent** (10) **Patent No.:** **US D1,044,794 S**
(45) **Date of Patent:** **** Oct. 1, 2024**

(54) **COMPUTER HOUSING**

(71) Applicant: **Weidmüller Interface GmbH & Co. KG**, Detmold (DE)

(72) Inventors: **Matthias Niggemann**, Dörentrup (DE); **Klaus Nolting**, Hamburg (DE)

(73) Assignee: **WEIDMULLER INTERFACE GMBH & CO. KG** (DE)

(**) Term: **15 Years**

(21) Appl. No.: **29/866,984**

(22) Filed: **Oct. 4, 2022**

(30) **Foreign Application Priority Data**

Aug. 4, 2022 (EP) 008931281-0002

(51) **LOC (14) Cl.** **14-02**

(52) **U.S. Cl.**

USPC **D14/300**; D14/348; D14/354

(58) **Field of Classification Search**

USPC D14/140.2, 140.4, 300–302, 308–314,

(57) **CLAIM**

The ornamental design for a computer housing, as shown and described.

DESCRIPTION

FIG. 1 is a front perspective view of a computer housing according to our invention;

FIG. 2 is a front elevation view of our design of FIG. 1;

FIG. 3 is a rear elevation view of our design of FIG. 1;

FIG. 4 is a right side elevation view of our design of FIG. 1;

FIG. 5 is a left side elevation view of our design of FIG. 1;

FIG. 6 is a top plan view of our design of FIG. 1; and,

FIG. 7 is a bottom plan view of our design of FIG. 1.

The broken lines in the drawing represent portions of the article which form no part of the claimed design.

1 Claim, 7 Drawing Sheets
